COMPRESSED AIR PROTECTIVE SHIELD

Filed Feb. 16, 1927

UNITED STATES PATENT OFFICE.

BYRON O. PATRICK, OF DES MOINES, IOWA.

COMPRESSED-AIR PROTECTIVE SHIELD.

Application filed February 16, 1927. Serial No. 168,573.

The purpose of my invention is to provide a compressed air protective shield of simple, durable and inexpensive and efficient construction.

More particularly, it is my object to provide a protective shield adapted to fit over the nose and mouth of the wearer and to provide a tube leading to the shield for discharging compressed air in jets directed away from the shield, and for also supplying air to the interior of the shield.

It is a further purpose of my invention to provide a head piece adjustable for different persons, supporting a vizor provided with openings for compressed air jets for directing air downwardly and away from the face.

It is still another purpose of my invention to provide such a device, which can be attached directly to the air cleaner or to air supply hose for air brushes or the like of the kind used for spray painting.

With these and other objects in view, my invention consists in the construction, arrangement and combination of the various parts of my compressed air protective shield, whereby the objects contemplated are attained, as hereinafter more fully set forth, pointed out in my claims, and illustrated in the accompanying drawings, in which:

Figure 1 is a perspective view of a compressed air protective shield embodying my invention.

Figure 2 is a detail, sectional view through the shield; and

Figure 3 is a rear elevation of the shield.

In recent years, the practice of applying paint by the spraying method has become common. The paint, duco, lacquer, or other liquid material is sprayed through a nozzle or spray gun by means of compressed air.

The practice involves considerable inconvenience for the painter who is compelled to breathe the fumes of the paint spray. With the new product known as duco, this spray becomes sometimes almost unendurable. Masks of the respirator type are extremely inconvenient to wear.

My device embodies the principle of supplying fresh air to the operator and of driving a screen of air away from his face for protecting him against the fumes and paint spray.

In all plants using the spray method of painting, there is supplied mechanism for furnishing compressed air and an air cleaner.

I connect the flexible tube indicated in the accompanying drawings by the reference numeral 10, either with the air cleaner or with the hose supplying air to the spray gun. 60

Connected with the hose 10 is a piece of piping 12, preferably of copper or of some material, which is pliable and can be bent to different shapes.

The piping 12 has a portion 12^a bent to a shape to fit over the back and top of the head. The connection 14 between the pipe 12 and the flexible tube 10 is intended to be at the back of the head, and there is mounted on the pipe 12 near the connection, a resilient curved, head band 16 to fit against and around the back part of the head. 65

At the forward part of the pipe 12 are formed the bent and rebent portions 12^b, so that the pipe 12 may be readily bent to fit 70 the heads of different sizes and shapes. 75

From the bent portions 12^b, the pipe 12 extends downwardly as at 12^c.

Supported on the portion 12^c of the tube 12 is another head clamp or head band 18 of resilient material. This head band and the tube portion 12^c support the vizor 20 of light weight material. At the outer edge of the vizor 20 is an air dispensing tube 22 arranged in communication with the tube section 12^c 80 by means of a branch 24.

The vizor pipe 22 has a series of vent holes 26 for discharging jets of air forwardly and downwardly and laterally and downwardly as shown for thus affording a fresh air 85 screen in front of the eyes of the wearer.

I provide a shield for the mouth and nose of the wearer, comprising a cup-shaped member 28 having at its free edge a flexible flap 30, preferably of rubber, adapted to fit 90 snugly to the face.

Connected with the lower end of the tube section 12 is a tube 32, which is coiled spirally around the shield 28, as shown in Figures 1 and 2.

The extreme end of the tube 32 is extended through the wall of the shield 28 and terminates in a portion 32^a closed at its end.

A short nozzle 34 extends inwardly into the shield 28 as shown in Figure 2 for supplying fresh compressed air to the wearer. 105

In the lower part of the tube 32 are holes 36 for emitting the surplus fresh air supplied to the interior of the shield and the breath of the wearer.

The spiral tube 32 is provided with a series of jet openings 38 so arranged as to throw 110

jets of fresh air outwardly and away from the face of the wearer, in a spray having generally the shape of a truncated cone with its smaller end at the shield. The air emitted from the spiral tube 32 also forms a fresh air screen in front of the face of the wearer.

My improved compressed air protective shield can be used in a great variety of ways and for many industrial purposes.

10 Assuming that it is to be used in a paint shop, it will be understood that the tube 10 is connected with the air cleaner or the air gun supply hose.

Wherever the device is used, the tube 10 is connected with a source of fresh, clean, compressed air. The tube 12 is bendable and has some degree of resiliency. The head bands or clamps 16 and 18 are resilient.

15 The tube 12 can be bent until the device fits any head.

A cap can be conveniently worn over my device.

20 Where my protective shield is used in connection with the compressed air painting apparatus, it will be noted that whenever the air is supplied to the tube leading to the air gun, it will likewise be supplied to my apparatus, and whether the air gun is in operation or not, the fresh air will be supplied to the user of my shield.

25 When the air to the tube 10 is turned on, a screen of fresh air will be discharged from the holes 26 as indicated by the arrows at 26^a for forming an air screen in front of the eyes of the wearer. Likewise the series of jet holes 38 will send out an air screen in front of the shield proper.

30 It will thus be seen that I have provided a compressed air protective shield to be worn as a headpiece by those who are engaged in the spray gun application of duco, lacquer or other liquid material used in the spraying process.

35 Incidentally, it may be said that the tube 32 has a sliding frictional engagement with the lower end of the tube section 12^c, so that the parts may be readily separated.

40 The air supplying the operator from the usual pressure tank passes through a small rubber or fabric hose attached to a properly constructed head gear at the back of the operator's head. This fabric tubing can also be attached to the supply tube a short distance back of the spray gun.

45 The head gear is constructed preferably of a suitable size of copper, aluminum or other practical tube material. The metal tubing passing over the head, conforming to the shape of the head, is twisted in the form of a waved line or ogee at the forward point, terminating at a point above the nose, thus giving perfect adjustment by expanding or contracting the head gear to fit any size of head.

50 At a proper point in the back, a soft metal

or other somewhat resilient band is preferably braised to the tube passing over the head. A similar band encircling the forehead is attached to the front part of the head gear tube. These bands do not entirely encircle the head, but leave spaces open at each side for thus making a sort of adjustable helmet.

Attached to the main tube at the front is a specially devised vizor.

55 Inserted in the head tube at the front of the device is the tube, which is bent spirally around the nose and mouth shield, which latter is arranged to fit snugly to the face. And in the specially provided vizor tube are drilled minute holes so arranged that when air pressure is provided, they cause an air screen.

Air for breathing purposes is furnished to the interior of the mouth and nose shield, thus enabling the operator at all times to breathe cool, pure air. The draft of air away from the shield draws away the surplus air provided for breathing and the impure air, which has been breathed.

60 A device of this kind can be worn and will afford the operator proper protection without the inconvenience inherent in the ordinary respiratory mask.

65 It will be understood that any suitable material, which is adapted for the purpose, may be employed in the manufacture of my device, and that it may be made in different sizes and shapes as may be desired for the purpose.

Changes may be made in the construction and arrangement of the various parts of the device without departing from the real spirit and purpose of my invention, and it is my intention to cover by my claims, any modified forms of structure or use of mechanical equivalents, or different materials, which may be reasonably included within their scope.

70 I claim as my invention:

1. In a device of the class described, a shield adapted to fit over the nose and mouth, a compressed air conductor leading to the shield, means on the shield, communicating with said conductor for discharging a plurality of jets of air away from the shield.

75 2. In a device of the class described, a shield adapted to fit over the nose and mouth, a compressed air conductor leading to the shield, means on the shield, communicating with said conductor for discharging a plurality of jets of air away from the shield, and means for projecting a jet of air into the shield.

80 3. In a device of the class described, a shield adapted to fit over the nose and mouth, a compressed air conductor leading to the shield, means on the shield, communicating with said conductor for discharging a plu-

rality of jets of air away from the shield, and means for projecting a jet of air into the shield, said shield having an outlet adjacent to certain of said first jets.

4. In a device of the class described, a shield adapted to fit over the nose and mouth, a compressed air conductor leading to the shield, means on the shield communicating with said conductor for discharging a plurality of jets of air away from the shield, and means for projecting a jet of air into the shield, said shield having an outlet.

5. In a device of the class described, a shield adapted to fit over the nose and mouth, a compressed air conductor leading to the shield, means on the shield communicating with said conductor for discharging a plurality of jets of air away from the shield, means for projecting a jet of air into the shield, said shield having an outlet, a vizor

element adapted to rest on the forehead, having a transverse tube provided with discharge openings directed outwardly and downwardly.

6. In a compressed air protective shield, a head gear made of bendable tubing and head engaging means, means for supplying compressed air to said tubing, a vizor supported on said head gearing having a tube communicating with said first tube and provided with small holes for emitting jets of air downwardly and away from the face of the wearer, a mouth and nose shield, means communicating with said first tube for supplying air to the interior of said shield and directing jets of air in a screen away from such shield. 25 30 35

Des Moines, Iowa, February 9, 1927.
